PILOT BURNER ARRANGEMENT

Thomas Esta Phares, Shelbyville, Ind., assignor
to Chambers Corporation, Shelbyville, Ind., a
corporation of Indiana

Application March 27, 1936, Serial No. 71,113

1 Claim. (Cl. 158—115)

My invention relates to pilot lights used on gas-burning equipment, such as gas-ranges, and particularly to a pilot-light arrangement of the explosion type. In this type of pilot-light, a supply of gas from the burner is mixed with air to form an explosive mixture and conveyed through a tube to the pilot burner. When the explosive mixture reaches the pilot burner, the gas within the tube explodes and creates a flame which 10 serves to ignite the burner.

I have found that equipment of this kind now available, while it may be satisfactory for gas of one of the three kinds now being used (natural, artificial, and bottled) will not operate satisfactorily with gases of other kinds due largely to the difference in proportions necessary to create an explosive mixture. It is the object of my invention to apply to pilot-light equipment of the explosive type means which will adapt the equipment for use in connection with burners burning different kinds of gas.

In carrying out my invention, I provide means for varying the effective area of the opening through which air is admitted to the explosion tube. In the preferred form of my invention, where a jet of gas enters the explosion tube through an opening in the lower wall thereof and serves also to induce a flow of air through such opening, my invention conveniently takes the form of a sleeve which surrounds the explosion tube and which by longitudinal adjustment thereon varies the effective size of the opening in the wall of the tube.

The accompanying drawing illustrates my invention: Fig. 1 is a plan view of a portion of a gas range showing a single burner and the pilot-light equipment associated therewith; Fig. 2 is a fragmental view similar to Fig. 1 with parts of the explosion tube broken away to show in horizontal section; and Fig. 3 is a vertical section on the line 3—3 of Fig. 2.

In the gas range, a portion of which is shown in Fig. 1, the main burners are supplied with gas from a manifold 10. Only one burner 11 is shown in Fig. 1, but it will be understood that any desired number of burners may be embodied, each being supplied with gas from the manifold 10 under control of a valve 12.

Also supplied with gas from the manifold 10 is a pilot burner 13, the supply of gas to which may be regulated by a valve 14.

The pilot burner 13 is conveniently centrally located with respect to the burners of the stove, and an explosion tube extends from each of such burners to a point adjacent the pilot burner. As

indicated in the drawing, each explosion tube is formed of two telescoping parts 15 and 16 in order that the tube may readily be adapted to ranges of different dimensions. Near its outer end, each of the tube-parts 16 is provided with a downwardly projecting boss 17 the lower end of which is conical in shape to conform to a tapered hole provided in the upper wall of the associated burner 11. Thus, the outer end of each of the explosion tubes is supported on its associated burner, while the inner end receives support from the housing usually provided for the pilot burner.

Both ends of each explosion tube are open; and, in addition, the tube-part 16 is provided in its lower surface with an opening 18 the outer end of which is located adjacent the boss 17. The boss 17 is provided with a downwardly opening recess with which there communicates a discharge port 19 adapted to direct from the burner 11 a jet of gas which rises obliquely upwardly toward the opening 18.

The construction as so far described is old. In operation, the pilot burner burns continually. When any of the valves 12 is opened, gas is supplied to the associated burner 11. On its way to the burner 11, this gas becomes mixed with sufficient primary air to produce a satisfactorily combustible mixture which is too rich in gas to be explosive. Some of the combustible mixture of gas and air is discharged through the port 19 and rises through the opening 18 into the interior of the explosion tube. The jet of gas emerging from the port 19 induces an inward flow of air through the opening 18, the opening 18 being of such a size that the amount of air admitted will create an explosive mixture within the explosion tube. When this explosive mixture fills the explosion tube and emerges from the inner end thereof adjacent the pilot burner 13, it is ignited; and, when the resultant burst of flame emerges from the outer end of the explosion tube, it ignites the gas emerging from the ports of the burner 11.

I find that in order for a device of this kind to operate satisfactorily the effective area of the opening 18 will differ materially with the type of gas used. To render the pilot-burner equipment adaptable for use with gases of different kinds, I therefore provide means for adjusting the effective size of the opening 18.

In the device illustrated in the drawing, the means employed for varying the size of the opening 18 takes the form of a sleeve 20 which surrounds the tube-part 16 and is longitudinally adjustable thereon. To aid in deflecting gas and

air into the explosion tube, the lower wall of the sleeve 20, at its outer end, may be bent downwardly to provide an inwardly and upwardly sloping tongue 21, as indicated in Fig. 3.

- 5 It will be apparent that by longitudinal adjustment of the sleeve 20 upon the tube 16 the effective area of the opening 18 may be regulated to vary the amount of air which is admitted into the explosion tube with gas from the port 19.
- 10 It thus becomes possible to produce in the explosion tube and explosive mixture of gas and air, irrespective of the type of gas supplied to the burner 11. For gases in which the explosive mixture is relatively lean, the sleeve 20 is moved inwardly to increase the effective area of the opening 18 thus increasing the quantity of air which enters the explosion tube with the gas. If the gas supplied to the burner 11 is one which requires a relatively small quantity of air to produce an
- 15

explosive mixture, the sleeve 20 is moved outwardly to decrease the effective area of the opening 18 and to decrease correspondingly the amount of air which enters the explosion tube with the gas.

5

I claim as my invention:

In combination, a main gas burner and a pilot burner remote therefrom, said main burner being provided in its upper wall with an auxiliary port, an explosive ignition tube extending from said main burner to said pilot burner and having in its lower wall adjacent said auxiliary port an opening for admission of gas from said port and of air, and a sleeve slidable upon said explosion tube to vary the effective size of said opening, the lower wall of said sleeve extending obliquely downward toward said port.
